UNITED STATES PATENT OFFICE.

OLIVER E. LEIB AND EUGENE B. WITTE, OF TRENTON, NEW JERSEY.

AUTOMATIC AIR-BRAKE AND STEAM COUPLING.

No. 824,034.

Specification of Letters Patent.

Patented June 19, 1906.

Application filed August 11, 1905. Serial No. 273,794.

To all whom it may concern:

Be it known that we, OLIVER E. LEIB and EUGENE B. WITTE, citizens of the United States, and residents of Trenton, in the county of Mercer and State of New Jersey, have invented a new and Improved Automatic Air-Brake and Steam Coupling, of which the following is a full, clear, and exact description.

Our invention relates to a device for replacing the flexible couplings now employed on air-brake systems between adjacent cars.

The principal objects of the invention are to provide means for effectively making an air-tight joint between two air-brake-system cars when the latter are coupled together and for automatically allowing an escape of air from each car when the cars are uncoupled or when one is released from the other; furthermore, to prevent the escape of all the air from the air-brake system in an uncoupled car, only allowing enough to escape to set the brakes, and to apply the device to both freight and passenger cars.

Reference is to be had to the accompanying drawings, forming a part of this specification, in which similar characters of reference indicate corresponding parts in all the figures.

Figure 1 is a longitudinal section of an automatic coupler, showing the principle of our invention and taken on the line 1 1 of Fig. 3. Fig. 2 is a plan of one end of the same. Fig. 3 is an end elevation, and Fig. 4 is a section on the line 4 4 of Fig. 3.

Upon the car to which the coupler is to be connected is placed a yoke 10, having sockets 11 for receiving trunnions 12 upon a cylinder 13. This cylinder is connected, by means of a coupler 14, with a flexible connection 15, and each in turn is connected with the air-brake system of the car through a coupling 16. This flexible connection is provided with an interior coiled spring 17 and an exterior spring 18 of the same character. The function of this connection is to conduct air from the system to the cylinder 13 and also to keep the cylinder in alignment with the axis of the car. The two springs 17 and 18 are sufficiently strong to swing the cylinder upon the trunnions and hold it in a straight position under ordinary conditions; but obviously they will yield to permit the car to pass around curves.

The cylinder 13 is provided with an extension 19, having a valve-seat 20. For engag-

ing this valve-seat a valve 21 is provided. This valve has a passage 22 opening into the conical surface of the valve, which seats upon the seat 20, and the passage is connected with the interior of a tube 23, upon which the valve 21 is mounted. This tube is provided with a disk 24, having a soft-rubber or other sheet of flexible material 25 upon its face. It is provided with circular bars 26, secured to the disk by means of screws or in any other suitable manner, these bars being concentric and serving to hold the soft-rubber or other flexible material in position. The passage through the center of the tube opens in the center of the interior of the disk, and, as the drawings 70 show, it is intended that two of these cups shall come together and form an air-tight joint between two cars. When the cars are coupled together, these two cups will press against each other and force their respective 75 valves 21 from the valve-seats 20, and consequently permit a communication of air between two cars.

The tube 23 is provided with a stuffing-box 28 to permit the reciprocating motion 80 which it has and prevent the passage of air around it. In order to provide a motive power for closing the valve 21 when pressure is removed from the cup 24, a collar 29 is 85 mounted between this collar and the stuffing-box.

The extension 19 is provided with a pair of ears 31, having tubes 32 secured thereto, and in each of these tubes is a spring 33, acting 90 upon a piston 34. These pistons 34 are connected by a yoke 35, having a passage 36 for receiving and guiding the tube 23. The spring 30 offers a certain amount of resistance to the opening of the valve, and the springs 33 afford a greater resistance, so that they yield 95 under such extraordinary shocks as those incurred in coupling cars.

From the parts so far described it will be readily understood that the air communication is kept up through the coupler while the cars are coupled together and the springs 30 compressed by the coupling devices by means of which the cars are connected, also that when a car is uncoupled from another and the consequent pressure of one cup 24 against the other is removed the spring 30 will operate to close the valve, and thus stop communication between the car and the outside air at this point.

It is necessary in the modern air-brake system to provide means for permitting air to be discharged from the system on the car when it is disconnected, so as to automatically apply the brakes. For accomplishing this purpose we provide the following mechanism: The cylinder or its extension is provided with a casing 37, having a valve-seat 38 for a valve 39. This valve is provided with a stem 40, 10 which is guided by a projection 41 on a cap 42, with which the casing is provided. A spring 43 is located at the end of the stem 40 to normally force the valve 39 into a position upon the seat 38 to prevent the passage of air 15 through the casing. The strength of this spring is sufficiently low to permit the normal air-pressure in the train to overcome it in order that the air-pressure may be automatically reduced by the desired amount; but to 20 prevent the loss of all the pressure in the car the strength of this spring is made within five or ten pounds of the air-pressure. A plug 44 is provided for adjusting the spring and for removing the pressure upon the 25 valve, so as to allow the air to escape when desired. The cap 42 is provided with openings 45 for permitting the air to escape when the valve is unseated.

In order to provide for automatically opening the valve 39 when the valve 21 is closed and for keeping this valve closed under other conditions, the stem 40 is provided with a pivoted catch 46, normally pressed by a spring 47 into engagement with a stationary 35 lug 48 upon the casing. It will be observed that when the valve is once forced to its seat the catch 46 will engage the lug 48 and will be held in closed position thereby. A spring 49 is mounted upon the casing and engages 40 a pivoted lever 50. This lever projects into the path of the valve 21, so that when the latter is closed it will engage it and cause it to engage the catch 46, so as to force the latter out of engagement with the lug 48. The 45 pressure of air in the casing being great enough to overcome the force of the spring 43, the valve 39 will be immediately unseated and air will be allowed to escape; but when the pressure reaches such a point that the 50 spring 43 can overcome it the latter will cause the valve to be seated again, and the catch 46 will again engage the lug 48, so as to hold the parts in the position shown. This provides for the automatic application of the 55 brake in case of the accidental parting of the train and for the conservation of as much air in the car system as can be provided for.

Although it will be obvious that any desired springs may be used according to the 60 conditions prevailing, in the preferred form to be used with the ordinary systems now in operation the spring 43 will be of sixty pounds, the spring 30 of one hundred and twenty-five pounds, and the springs 33 will 65 be of greater strength than the spring 30.

The parts so far described are such as are required when the device is to be applied to freight-cars. When, however, it is to be applied to a passenger-car system, we use additional elements, which are illustrated in the 70 drawings, in connection with the parts described above, but which will be omitted when the system is to be applied to freight-cars only. The parts which are added for use in passenger-cars are a cylinder 13^a, 75 placed adjacent to the air-brake cylinder 13 and to be used for the air signal system, and a cylinder 13^b, placed, preferably, below the other two cylinders and used for steam. The air signal-cylinder 13^a is provided with a casing 37^a, similar to the casing 37, and other elements corresponding to those within the casing 37 and the cap 42. As these parts on the air signal system are not shown in section, the only ones which appear are a cap 42^a and 80 a screw 44^a. It will be understood that these parts work in the same manner as those in the device described above.

Having thus described our invention, we claim as new and desire to secure by Letters 90 Patent—

1. In an air-brake coupler, the combination of a cylinder having a valve-seat, a guide resiliently mounted upon the cylinder, a valve for said seat in the cylinder, said valve 95 having a passage, a tube for supporting said valve and communicating with said passage, said tube engaging said guide, and a cup upon the tube having a yielding surface for forming an air-tight joint. 100

2. In an air-brake coupler, the combination of a cylinder, means for pivotally supporting it, a valve in the cylinder, a tube for supporting said valve, said tube communicating with the interior of the cylinder when the valve is open, a collar adjustably mounted on the tube, a spring located between the collar and the spring for forcing the tube in such a direction as to close the valve, and movable means for guiding the tube. 110

3. In an air-brake coupler, the combination of a cylinder, means for pivotally mounting the cylinder upon a car, a tubular connection between the cylinder and an air-brake system upon a car, a pair of coiled 115 springs one inside of said connection and the other upon the outside of the connection, for normally holding said cylinder in a certain position upon the car, a valve in the cylinder, and means for automatically closing the 120 valve when the car is separated from an adjacent car.

4. An air-brake coupler, comprising a tube, a cup thereon having a yielding surface for forming a tight joint with a companion cup, 125 resilient means for forcing the tube longitudinally in a direction toward the cup, and a valve on the tube having a passage to the interior of the tube, in combination with a cylinder having a valve-seat for said valve, 130

means for supporting the tube, and means for permitting the escape of air from the cylinder when the valve is forced to its seat.

5. An air-brake coupler comprising a cylinder, a valve for controlling the passage of air therethrough, means for closing said valve, and means adapted to be engaged by the valve for permitting the escape of air when the valve is closed.

10. 6. An air-brake coupler comprising a cylinder, a valve for controlling the passage of air therethrough, means for closing said valve, and means adapted to be engaged by the valve for permitting the escape of air when the valve is closed; said means comprising a casing connected with said cylinder and having a valve-seat, a valve for said seat, means for normally forcing the valve to its seat, and a lever disposed in the part of the 15 first-mentioned valve.

7. An air-brake coupler, comprising a cylinder having a movable valve, means for closing said valve, a lever located in position to be engaged by said valve when closed, a 20 casing on the cylinder, a valve in the casing, and means for holding said valve in closed position, said lever being adapted to engage said means and render it inoperative.

8. An air-brake system, comprising a cylinder, a movable valve therein, a casing connected with said cylinder, a valve in the casing for allowing the escape of air from the cylinder, a spring for forcing said valve to its seat, said spring being of such strength that 25 the normal air-pressure within the car will overcome it, a stationary lug, a movable catch connected with the valve in the casing, and means for disengaging the catch from the lug when the first-mentioned valve is moved 30 to its seat.

9. An air-brake system, comprising a casing having a valve-seat, a cap for the casing having passages to the open air, a valve for said seat, a valve-stem, a spring for forcing 45 the valve to its seat, an adjustable plug for controlling the spring, a catch pivotally mounted upon the valve-stem, a stationary lug, a spring for forcing the catch into engagement with the lug, and a lever pivoted 50 on the lug and adapted to engage the catch to disengage the latter from the lug.

10. An air-brake system comprising a casing having a valve-seat, a cap for the casing having passages to the open air, a valve for 55 said seat, a valve-stem, means for forcing the valve to its seat, an adjustable plug for controlling said means, a catch mounted upon the valve-stem, a lug, means for forcing the catch into engagement with the lug, and 60 means on the lug adapted to engage the catch to disengage the latter from the lug.

11. An air-brake system, comprising a cylinder, a movable valve therein, a casing connected with said cylinder, a valve in the casing 65 for allowing the escape of air from the

cylinder, and a spring for forcing said valve to its seat, said spring being of such strength that the normal air-pressure within the car will overcome it.

12. An air-brake coupler, comprising a cylinder, a valve for controlling the passage of air therethrough, means for controlling said valve, and means adapted to be engaged by the valve for permitting the escape of air when the valve is closed, said means comprising a casing connected with said cylinder and having a valve-seat, a valve for said seat, and means disposed in the path of the first-mentioned valve for operating said last-mentioned valve.

13. An air-brake coupler, comprising a tube, resilient means for forcing the tube longitudinally and a valve on the tube, the tube having a passage to its interior, in combination with a cylinder having a valve-seat for 85 said valve, means for supporting the tube, and means for permitting the escape of air from the cylinder when the valve is forced to its seat.

14. An air-brake coupler, comprising a cylinder, means for pivotally mounting the cylinder upon a car, a flexible connection between the cylinder and an air-brake system upon the car, and a pair of coil-springs, one inside of said connection and the other upon 95 the outside thereof for normally holding said cylinder in a certain position upon the car.

15. An air-brake coupler, comprising a cylinder, a valve in the cylinder, a tube for supporting said valve, said tube communicating 100 with the interior of the cylinder when the valve is opened, a collar adjustably mounted on the tube, and a spring for forcing the tube in such direction as to close the valve.

16. An air-brake coupler, comprising a cylinder having a valve-seat, a guide resiliently mounted upon the cylinder, a valve for said seat, and a tube for supporting said valve, said tube engaging said guide.

17. An automatic air-coupler having three 110 cylinders each provided with a valve-seat, a guide resiliently mounted upon the cylinders, a valve in each cylinder for the valve-seats, each of said valves having a passage, a tube for supporting each valve and communicating 115 with the passage, said tubes engaging said guide, and connections from the three cylinders for conducting air from an air-brake system, air from an air signal system, and steam into the three cylinders respectively.

In testimony whereof we have signed our names to this specification in the presence of two subscribing witnesses.
